BOTTLE CARRIER

Joseph C. Kuchel, Arlington, Va.

Application July 25, 1950, Serial No. 175,820

5 Claims. (Cl. 294—87)

1

This invention relates to bottle carriers of the type resembling fillers for beer and soft drink cases, and in particular this invention relates to a carrier having a handle formed in a centrally disposed panel with bottle carrying cells on the sides of the panel and in which bottles are retained in the cells by a friction element that permits the carrier to be placed over bottles in a case so that the bottles may be picked up thereby and also that permits the bottles to be dropped through the carrier by pressing downwardly upon the upper ends of the bottles with the carrier in an elevated position.

The purpose of this invention is to provide a bottle carrier in which bottles may be inserted in cells therein by forcing the carrier downwardly over the bottles thereby eliminating the necessity of dropping each bottle in a cell or pocket of the carrier.

In the conventional type of bottle carrier where bottles are placed in cells having closed lower ends it is necessary to place the bottles in the cells individually and also remove each bottle from its cell by withdrawing the bottle from the upper end of the cell. This requires considerable time and the percentage of breakage of bottles resulting therefrom is large. With this thought in mind this invention contemplates a carrier that is placed over a group of bottles and with the bottles in registering relation with cells therein the carrier is pressed downwardly over the bottles whereby friction gripping elements in the cells retain the bottles in position and when it is desired to discharge the bottles from the cells the carrier with the bottles therein is positioned over a point where it is desired to deposit the bottles and by pressing downwardly upon the upper ends of the bottles until the necks of the bottles are positioned between the friction gripping elements the bottles are dropped freely from the carrier.

The object of this invention is, therefore, to provide a bottle carrier in which the bottle carrying cells are so formed that bottles may be picked up and dropped through the lower end of the carrier.

Another object of the invention is to provide a carrier in which bottles are frictionally held that is adapted to receive conventional bottles so that it is not necessary to change the design or shape of the bottles.

A further object of the invention is to provide a bottle carrier in which bottles are frictionally held in cells which is of a simple and economical construction.

With these and other objects and advantages in view the invention embodies a bottle carrier

2 having a longitudinally disposed centrally positioned panel with a hand opening in the upper part thereof and with sections on the ends extended to form bottle receiving cells and with intermediate strips of material formed to provide intermediate cells, and with resilient gripping elements mounted on pins in the corners of the lower ends of the cells.

Other features and advantages of the invention will appear from the following description taken in connection with the drawings wherein:

Figure 1 is a view illustrating a plurality of the improved bottle carriers in a case with part of the case broken away and shown in section and with one of the carriers positioned above a group of bottles.

Figure 2 is a plan view of the case shown in Figure 1.

Figure 3 is a longitudinal section through the case illustrated in Figure 1.

Figure 4 is a plan view of one of the bottle carriers.

Figure 5 is a longitudinal section through the carrier taken on line 5—5 of Figure 4.

Figure 6 is a cross section taken on line 6—6 of Figure 4, the said section being taken through the corners of the cells and showing friction gripping elements in opposite corners in the dotted lines.

Figure 7 is a sectional plan through a corner of one of the cells showing a resilient element mounted on a pin therein.

Figure 8 is a detail showing a vertical section through one of the cells illustrating the position and mounting of the resilient elements therein.

Figure 9 is a detail illustrating the construction of the center panel with the cells formed on opposite sides of the ends thereof.

Figure 10 is a detail illustrating the method of forming the intermediate and end cells which are diagonally positioned on opposite sides of the center panel.

Referring now to the drawings wherein like reference characters denote corresponding parts the improved bottle carrier of this invention includes a center panel 10 having end cells 11 and 12 positioned on opposite sides of the ends thereof, intermediate cells 13 and 14, and oppositely positioned cells 15 and 16, and each of the cells is provided with four balls of rubber or other resilient material as indicated by the numeral 17, the balls being mounted on pins 18, as illustrated in Figures 7 and 8.

55 In the design shown the center panel 10 is formed of a length sufficient to provide cells for three bottles of the conventional soft drink or

beer bottle type and the cell 11 at one end is formed with a transversely disposed panel 19 extended from the end of the panel 10, a longitudinally disposed panel 20 extended from the end of the panel 19 and a transversely disposed panel 21 extended from the edge of the panel 20 and parallel to the panel 19. The panels 19, 20 and 21 extend from the lower end of the panel 10 to a point 22 which is spaced from the upper end of the panel 10.

The cell 12 is formed with a transverse panel 23 extended from the opposite end of the panel 10, a longitudinally disposed panel 24 extended from the outer edge thereof and with a transversely disposed panel 25 extended from the edge of the panel 24.

The panel 10 is also provided with a hand opening 26 and spaced vertically disposed slots 27 and 28 extend upwardly therein from the lower edge.

The cells 14 and 15 are formed as illustrated in Figure 10 with a longitudinally disposed panel 29 positioned to be placed against the opposite face of the panel 10, a transversely disposed panel 30 extended from the edge of the panel 29, a panel 31 extended from the edge of the panel 30 and parallel to the panel 29, a panel 32 extended from the edge of the panel 31, across the end of the panel 29 and extended on the opposite side thereof to the edge of a panel 33 which with the parts assembled is in the same plane as that of panel 24. From the edge of the panel 33 the panel 34 extends to the surface of the center panel 10 with the edge 35 of the panel 34 positioned against the surface of the panel 10. The panel 32 is provided with a vertically positioned slot 36 and with the lower part of the panel 32 extended through the slot 28 the slot 26 receives the upper part of the panel 10. This section forms the cells 15 and 14 and a similar section with the lower section of the transversely disposed panel corresponding with the panel 32 is positioned in the slot 27 thereby forming the cells 13 and 16.

With the cells positioned in this manner the abutting panels are secured together by rivets 37 and each cell is provided with four of the resilient elements 17 which are mounted on the pins 18, the ends of which are bent or crimped on the outer surfaces of the panels as shown in Figure 7.

By this means a carrier as generally referred to by the numeral 38 in Figure 1 may be placed over a group of bottles with the caps and necks of the bottles guiding the bottles upwardly through the cells as the carrier is pressed downwardly over the bottles. With the lower end of the carrier in engagement with the flat surface upon which the bottles are positioned as illustrated in Figures 5 and 6 the bottles are resiliently held in the carrier by the friction balls or elements 17. The bottles may be carried by the carrier from one position to another and when it is desired to deposit the bottles in a case 39 or the like it is only necessary to suspend the carrier over the position desired and by pressing downwardly on the upper ends of the bottles, the bottles will drop through the carrier into the case, or into a cabinet or the like.

It will be understood that other modifications may be made in the design and arrangement of the parts without departing from the spirit of the invention.

What is claimed is:

1. A bottle carrier comprising a plurality of vertically disposed bottle carrying cells the upper and lower ends of which are open, a center

panel having an upwardly extended end with a hand receiving opening therein positioned between the cells and rubber ball like friction elements positioned in the cells and spaced from the lower ends thereof for frictionally retaining bottles in the cells.

5. A bottle carrier comprising a plurality of vertically disposed bottle receiving cells the upper and lower ends of which are open, a center panel 10 having an upwardly extended end with a hand receiving opening in the said upwardly extended end, said panel positioned between rows of cells, and rubber ball like friction elements journaled in the cells and spaced from the lower ends thereof for frictionally retaining bottles in the cells.

10. A bottle carrier comprising a plurality of vertically disposed bottle receiving cells the upper and lower ends of which are open, a center panel having an upwardly extended end with a hand receiving opening in the said upwardly extended end, said panel positioned between rows of cells, and rubber ball like friction elements journaled in the cells and spaced from the lower ends thereof for frictionally retaining bottles in the cells.

15. A bottle carrier comprising a plurality of vertically disposed bottle receiving cells the upper and lower ends of which are open, a center panel having an upwardly extended end with a hand receiving opening in the said upwardly extended end, said panel positioned between rows of cells, and friction elements journaled in the cells and spaced from the lower ends thereof for frictionally retaining bottles in the cells, said friction elements positioned whereby upon the application of pressure to bottles in the cells the bottles

20. A bottle carrier comprising a plurality of vertically disposed bottle receiving cells the upper and lower ends of which are open, a center panel having an upwardly extended end with a hand receiving opening in the said upwardly extended end, said panel positioned between rows of cells, and friction elements journaled in the cells and spaced from the lower ends thereof for frictionally retaining bottles in the cells, said friction elements positioned whereby upon the application of pressure to bottles in the cells the bottles pass through the cells.

25. A bottle carrier, the combination which comprises a vertically disposed center panel having an upwardly extended end and having a hand receiving opening in the said upwardly extended end, rows of square cells having side and end walls positioned on the sides of and carried by the center panel, and rubber ball like friction elements in the corners of the cells and spaced from the lower ends thereof for frictionally retaining bottles in the cells.

30. A bottle carrier, the combination which comprises a vertically disposed center panel having an upwardly extended end and having a hand receiving opening in the said upwardly extended end, rows of square cells having side and end walls positioned on the sides of and carried by the center panel, and rubber ball like friction elements in the corners of the cells and spaced from the lower ends thereof for frictionally retaining bottles in the cells.

35. A bottle carrier, the combination which comprises a vertically disposed center panel having an upwardly extended end and having a hand receiving opening in the said upwardly extended end, cell forming end sections the upper edges of which are spaced from the upper end of the center panel extended in opposite directions from the ends of the center panel with end walls thereof perpendicular to the center panel, with side walls parallel to the center panel and with inner walls also perpendicular to the center panel, thereby forming vertically disposed bottle receiving cells on the opposite sides of and at the ends of the said center panel, corner and intermediate cell forming sections each having end walls perpendicular to the center panel and side walls parallel to the center panel and with connecting walls between the cells provided with vertically disposed slots for receiving the center panel, and friction elements in the corners of the cells and spaced from the lower ends thereof for frictionally retaining bottles in the cells.
